UNITED STATES PATENT OFFICE.

WILLIAM CROSS, OF WINNIPEG, CANADA.

APPARATUS FOR USE IN UNITING IRON AND STEEL PLATES.

SPECIFICATION forming part of Letters Patent No. 788,888, dated May 2, 1905.

Application filed May 25, 1904. Serial No. 209,765.

To all whom it may concern:

Be it known that I, WILLIAM CROSS, residing at Winnipeg, in the Province of Manitoba, Canada, have invented certain new and useful 5 Improvements in Apparatus for Use in Uniting Iron and Steel Plates, of which the following is a specification.

My present invention relates to a certain new and improved tool for use in uniting iron 10 and steel plates in boiler construction and the like, and it particularly seeks to provide a device of this character in which the plates to be joined are tightly held in their correlative position and may be alternately drilled and 15 tapped and a plug or bolt inserted into the drilled and tapped apertures.

With other objects in view, which will be hereinafter apparent, the invention comprises certain novel construction and combination 20 of parts, all of which will be first described in detail, and then specifically pointed out in the appended claims, reference being had to the accompanying drawings, in which—

Figure 1 is a side elevation showing my improved tool in use for drilling the plug-aperture and showing how the patch is tightly held against the boiler-plate during the drilling, &c., process. Fig. 2 is a longitudinal section of the drill. Fig. 3 is a cross-section 30 on the line 3-3 of Fig. 2. Figs. 4, 5, 6, and 7 are cross-sections on the lines 4-4, 5-5, 6-6, and 7-7 of Fig. 2. Fig. 8 is a detail view hereinafter referred to.

Referring now to the accompanying drawings, in which like numerals and letters of reference indicate like parts in all the figures, 35 1 designates the boiler fire-box, which may be of the ordinary construction and which *per se* forms no part of this invention.

When my invention is used in patching locomotive boxes, boilers, and the like, the patch-plate 2 is formed in any desired shape, depending upon the nature of the break in the boiler, and includes the ordinary stay-bolt 45 apertures 2^a, as shown. Interposed between the patch-plate and the main plate is any suitable liner 3. (Shown in detail in Fig. 8.) I first secure the plate in its place with temporary bolts an eighth of an inch less in diameter than the standard to be used to secure the

patch, the liner being placed in position at the same time. I then adjust the drill and tapping-machine over the place where the hole is to be drilled and force it hard against the plate to hold the patch-plate firmly against 55 the copper liner and the boiler-plate. The patch-plate will at the same time be firmly beaded upon the copper joint by the use of a hammer. After the drilling-machine has been placed in position the hole is drilled and then 60 tapped, and the screw-plug is then inserted, all of which operations will be presently more fully explained.

By reference to Figs. 1 to 7, inclusive, it will be seen the drilling-machine comprises a 65 body portion or frame 5, from which the laterally-extending radial arms 5^a 5^b extend in opposite directions. The arm 5^a terminates in an elongated eye portion 6 to permit of the insertion of the drill-holder-adjusting screw 70 7, which has a spherical head 7^a, apertured, as at 7^b, to receive a rod for turning the same. The arm 5^a from the eye 6 to where it joins the body 5 has a longitudinal bore 6^a, threaded, as at 6^b, to receive the screw 7, and enlarged, 75 as at 6^c, to receive a frame and guideway for the drill-chuck-carrying shaft 8, the end 8^a of which shaft 8 fits the bore 6^c and is provided with a semispherical indentation or pocket 8^b at its end to coöperate with the correspondingly-formed end 7^c of the screw 7.

To the extreme end of the eye portion 6 is integrally formed an extension 6^d, threaded, as shown, to receive the elongated turning-sleeve 6^d, which is formed with wrench-receiving faces 6^e and a plate-engaging point or center 6^f, by means of which sleeve and its screw connection the tool is tightly forced against the plate to cause it to become tightly seated against the patch and the boiler-plate 90 during the operation of boring, tapping, and inserting the securing-plug.

The arm 5^b extends in a direction diametrically opposite to the arm 5^a and in alignment therewith, and the said arm 5^b is provided with a longitudinal bore 5^c, through which the drill-chuck-carrying shaft 8 passes, and this bore 5^c is enlarged, as at 5^d. The bore 5^c is circular in cross-section to form a guideway for the shaft 8, and the enlarged 100

bore 5^d is also circular in cross-section to form a guideway from the drill-chuck 8^f, which is secured to the end of the shaft 8 and which is susceptible to longitudinal adjustment in the bore 5^d. The arm 5^b, where the enlarged bore 5^d begins, is cut away, as at 5^e, to permit of ready access to the chuck to insert or remove the drill, tap, or plug, and the end of the arm 5^b is formed with a head or hammer portion 5^g, which is likewise circular in cross-section, but which is cut away on one side, as at 5^m, to form a sight-opening.

Reverting again to the shaft 8, it will be seen the said shaft is provided with a longitudinal groove 8^c to receive the key 8^d, which has shoulder portions 8^e 8^f, and is so formed as to be received by the key-slot 8^x of the pinion 8^g, mounted on the shaft 8 within the body portion 5, which body portion 5 is in the nature of a ring or circular frame and is also provided with a hub 10 at right angles to the arms 5^a 5^b, but in the same plane therewith. The hub 10 is apertured to receive a stub drive-shaft 11, to which is keyed the pinion 12, which pinion 12 meshes with the pinion 8^g, whereby when motion is imparted to the drive-shaft 11 the same will be transmitted, through the pinions 12 and 8^g, to the drill-carrying shaft 8. The shaft 11 is also provided with a squared end 11^a to receive a crank 12 or other power-transmitting means.

After the patch has been put into position and the tool adjusted with respect to the place where the hole is to be drilled, as before indicated, the desired tension or pressure is brought to bear on the patch at this point to hold the same, as well as the drill, in place during the boring, tapping, and plugging operation by means of the sleeve 6^d. After placing the required drill D (see Fig. 1) in the chuck power is applied to the shaft 11, which is transmitted through the pinions 12 and 8^g to the shaft 8 to impart rotary motion thereto to operate the drill, the desired feed of the drill being given through the medium of the screw 7. After the aperture has been drilled the drill is withdrawn therefrom and removed from the chuck and a tap is inserted in the chuck in the place of the drill without removing the machine from its position. The hole having been drilled is then tapped by operating the shaft 11, and through the gears 12 and 8^g the shaft 8, as before. As soon as the desired tap is made the shaft 8 is reversed and rotated to remove the tapping-tool from the bore, which tool is then removed from the chuck and replaced by a steam-tight plug 4, which is provided with a squared end 15^a to enter the chuck and a threaded portion 4^b to enter the tapped bore of the patch-plate, the copper liner, and the boiler-plate. This plug is provided with a circumferential groove or nick 4^c, whereby after the plug has been screwed in the previously-tapped bore by rotating the shaft 8 the squared portion 15^a may

be broken off to leave the plug as shown in Fig. 2. The tool is then removed from its present position and adjusted in another place for performing the next boring, tapping, and plugging operation at another point, all of which operations are performed in the same manner as for the first boring, tapping, and plugging operation.

From the foregoing description, taken in connection with the accompanying drawings, it is thought that the complete construction, operation, and many advantages of my invention will be readily apparent to those skilled in the art to which it appertains, and I desire to say that I do not confine myself to the exact construction and arrangement of parts, as it is obvious that slight changes in the detail construction, arrangement, and combination of parts may be made without departing from the scope of the invention or the appended claims.

Having thus described my invention, what I claim, and desire to secure by Letters Patent, is—

1. An apparatus of the character described, comprising a body having a pair of radial arms, one of said arms including an elongated eye portion and a threaded extension, an elongated threaded sleeve for coöperating with said extension, a drill operating and carrying means mounted within said body and arms, and means for adjusting said drill operating and carrying means, said adjusting means having a portion movable in said elongated eye portion of the arm, for the purposes specified.

2. An apparatus of the character stated comprising a body having a pair of radial arms, one of said arms including an elongated eye portion and a threaded extension, an elongated threaded sleeve for coöperating with said extension, said first arm having an axial bore including a reduced threaded portion, a bolt having a head held in said elongated eye portion with its end in said reduced threaded portion, said second arm having a longitudinal bore and a transverse slot, said longitudinal bore including a reduced portion and an enlarged portion, a drill - chuck rotatably mounted and longitudinally movable in said enlarged bore portion, a shaft secured to said chuck and passing through said reduced bore portion of the second arm and extending into the bore of the first arm into engagement with said bolt, and means for imparting rotary motion to said shaft, for the purposes specified.

3. A drilling apparatus comprising a frame including a central portion and radial alining arms, the first of said arms being longitudinally bored to form a guideway, a cross-slot merging with said guideway, said arm terminating in an abutting head having a slot merging with said bore and cross-slot to form a sight-opening, and a drill-chuck rotatably mounted and axially adjustable in said longi-

tudinal bore, said second arm being longitudinally bored and including an eye portion and terminating in a threaded projecting member, a sleeve coöperatively mounted on said 5 threaded projecting member, said second-arm bore including a threaded portion, a bolt having a head held in said eye and threaded portions, a shaft secured to said chuck and pass-

ing through said first and second arm bores, and abutting said bolt end, and means for driving said shaft, substantially as shown and described.

WILLIAM CROSS.
